CONVERSION OF HYDROCARBON OIL

Richard J. Dearborn, Summit, N. J., assignor to
The Texas Company, New York, N. Y., a cor-
poration of Delaware

Application August 6, 1936, Serial No. 94,544

1 Claim. (Cl. 196—49)

This invention relates to the conversion of high boiling hydrocarbons into lower boiling hydrocarbons suitable for motor fuel and pertains more particularly to the processing of relatively heavy oils not amenable to the high temperature drastic cracking treatment essential to produce maximum yields of high anti-knock gasoline, due to their tendency to form coke.

One factor limiting the cracking treatment of the heavy oils, such as crude, reduced crude, heavy gas oil, and other oil stocks containing constituents difficult to vaporize is the rapid formation of coke, which fouls the heating tubes and other parts of the cracking equipment. For each particular heavy oil cracked under conventional methods there is a more or less fixed relationship between the amount of coke formed and gasoline produced at various degrees of cracking. In view of this relationship, the cracking temperature and the length of time at which the oil is subjected to cracking treatment is limited to avoid the formation of troublesome coke deposition at the sacrifice of gasoline yield in this initial cracking stage in order to extend the length of operating runs.

In accordance with present practice these heavy oil stocks are subjected to a relatively mild cracking treatment, commonly known as viscosity breaking, regulated to produce an optimum yield of intermediate clean condensate. The cracked products are then separated into vapors and residue and the vapors fractionated to condense and separate the higher boiling constituents as intermediate cycle stock from the gasoline produced from the process. The residue resulting from this viscosity breaking treatment, with or without further treatment to free it of any lower boiling constituents contained therein, is ordinarily rejected from the process as fuel oil or converted into solid coke by further treatment.

The intermediate cycle stock, formed by the initial mild cracking of the heavy oil, is then subjected to high temperature drastic cracking treatment in a second stage to produce an optimum yield of gasoline of high anti-knock characteristics. The character of the intermediate cycle stock permits the production of a much larger yield of high anti-knock gasoline with a lesser amount of carbon deposition than do the original crude stocks or other stocks containing constituents difficult to vaporize.

Another factor, in addition to the formation of coke, limiting the extent of cracking in the second stage is the formation of gaseous constituents boiling below the range of gasoline. While these gases do not interfere with the operation of the process, they do limit the yield of gasoline produced, and in many cases the extent of cracking of the intermediate gas oil in the sec-

ond stage is limited to avoid excessive gas losses rather than to avoid coke difficulties.

My invention has for its principal object the improvement of the process of the general nature above outlined so as to produce a better yield of high anti-knock gasoline with a lesser amount of processing and equipment.

In accordance with my invention the intermediate cycle stock resulting from the viscosity-breaking treatment, after undergoing high temperature cracking treatment, in the second stage for a maximum period, limited to avoid troublesome coke deposits, is merged with the residue from the viscosity-breaking treatment and the combined products thereafter subjected to further cracking treatment after which the products are separated from vapors and residue and the vapors fractionated in a conventional manner.

According to another phase of my invention a light intermediate cycle stock formed by fractionating the vapors from the second stage is subjected to further independent cracking treatment in a third stage and the products from the third stage treatment introduced into the zone in which the vapors from the viscosity-breaking treatment are fractionated so that the higher boiling constituents from the third stage treatment are passed to the second stage for further treatment therein.

When carrying out the process in accordance with the principles of my invention, as briefly outlined above, the ultimate gas loss from the process may be substantially below what would normally be expected from the extent of cracking to which the charging stock has been subjected and the total yield of gasoline is greater than may be expected from the extent of cracking. In other words, the ratio of gasoline produced to the amount of gas formed is greater than may be expected from the character of the treatment given.

While the cause of these results has not been definitely established, there are a number of possible explanations. First, the heavy residual constituents introduced into the products undergoing high temperature vapor phase cracking in the second stage after these products have undergone extensive cracking may serve as a solvent for asphaltenes and carboils which begin to form as the cracking proceeds and prevent deposition of these materials on the walls of the heating tubes, thus permitting a greater amount of cracking of the clean condensate stock in the second stage.

Second, the heavy residual constituents introduced into the products undergoing high temperature vapor phase cracking after these products have undergone extensive cracking so as to form a relatively high concentration of gaseous constituents may react with such gases to form hy-

drocarbons in the gasoline boiling range, or these heavy residual constituents may tend to promote the polymerization or alkylation of such gases into higher boiling compounds within the gasoline boiling range.

Third, the cracked products undergoing conversion in the second stage, upon contacting with the residue from the viscosity-breaking treatment, may serve as a carrier or diluent for the residual constituents and permit more extensive cracking of the residue.

Whatever the underlying causes may be, very definite advantages may be realized by processing the oil in accordance with my invention.

Other more specific objects of my invention will be apparent from the more detailed description hereinafter in which reference is made to the accompanying drawing diagrammatically illustrating an apparatus suitable for carrying out my invention.

Referring now to the drawing, the reference numeral 10 designates a charging line through which fresh charging oil is introduced into the system. This fresh charging oil is preferably a crude stock, such as crude, topped or reduced crude, but may be a heavy gas oil. The fresh charging stock passing through line 10 is forced by means of pump 11 located therein to a heating coil 12 located in the furnace 13 wherein a fresh charging oil is heated to a cracking temperature after which it discharges through transfer line 14 into a separating chamber 15.

The temperature and time of treatment of the oil during its passage through the coil 12 will depend upon the character of the oil charged thereto. When operating on reduced crude the oil may be heated to a temperature of from 800° to 900° F., for example, and maintained at cracking temperature for a period sufficient to convert 30% thereof into constituents boiling below the boiling range of the charging oil of which from 8 to 15% may be within the gasoline boiling range.

The products, after being introduced into the separating chamber 15, separate into vapors and residue, the vapors passing overhead through line 16 to a fractionating tower 17. The upper end of the separating chamber 15 may be provided with baffles to knock down entrained liquid prior to the passage of the vapors into the fractionating tower 17, and a reflux oil may be introduced into the top of the chamber.

Vapors introduced into the fractionating tower 17 are subjected to fractionation to separately condense insufficiently cracked constituents as reflux condensate. The fractionating tower is provided with suitable gas liquid contact elements, such as bubble trays, to effect rectification of the vapors passing therethrough. The upper end of the fractionating tower 17 is provided with suitable cooling means such as trimming coil 18 to regulate the top temperature so as to condense insufficiently cracked constituents within the fractionating tower 17. Sufficiently cracked constituents remain uncondensed in the tower 17 and pass overhead through line 19 to a condenser 21, wherein the sufficiently cracked vapors within the gasoline boiling range are condensed. Products from the condenser 21 pass through line 22 to a receiving drum 23 wherein fixed gases separate from the desired distillate. The fixed gases pass overhead through line 24 provided with a valve 25 for regulating the back pressure on the system and may be passed to a suitable gas recovery plant not shown. The desired distillate separated in the receiving drum

23 is withdrawn therefrom through line 26. If desired, a portion of this distillate may be returned to the upper portion of the fractionating tower 17 to serve as a reflux medium therein.

Condensate formed in the fractionating tower 17 is withdrawn therefrom through line 27 provided with pump 28 and is forced through heating coil 29 located in the furnace 13 wherein the oil is subjected to high-temperature, vaporphase cracking conditions. The oil, after being heated to the desired cracking temperature in coil 29, continues through a soaking coil 33, located in the convection section of the furnace, where it is maintained at high cracking temperature until cracking has proceeded to a point just short of that at which asphaltenes and carboids begin to precipitate on the walls of the heating tubes. These cracked products are then merged with residue separated from the cracked products from the heating coil 12 in the separating chamber 15. To this end the residue is withdrawn from the bottom of the chamber 15 through line 31 provided with pump 32 and is injected into the stream of cracked products undergoing final conversion in the soaking coil 33.

The mixture of residue and cracked products from coil 29 is subjected to further conversion conditions in the final section of the tubular soaking coil 33, after which it discharges through line 34 to a separating chamber 35 wherein vapors separate from residue.

The residue from the separator 15 may pass through lines 31 and 65 to the outlet of the heating coil 29 and then merge with the vapor phase products undergoing cracking, or a portion or all of the residue may pass through lines 31 and 66 and merge with the vapor phase products at one or more points in the final section of the soaking coil 33.

The upper section of the chamber 35 may be provided with baffles for the purpose of removing entrained liquid before passing overhead through line 36 to the bottom section of a fractionating tower 38. The fractionating tower 38 is provided with suitable fractionating elements, such as bubble trays, for effecting vapor-liquid contact, and the top temperature is regulated by a trimming coil 39 or by direct refluxing to condense insufficiently cracked constituents.

Sufficiently cracked constituents, together with fixed gases, pass overhead through line 40 to a condenser 41 wherein the sufficiently cracked constituents within the boiling range of gasoline condense as a final distillate. Products from the condenser 41 pass through line 42 to a receiving drum 43 wherein the desired distillate separates from the fixed gases. The fixed gases pass overhead through line 44 provided with a valve 45 for regulating the back pressure on the system and may pass to a suitable gas recovery plant not shown. The desired distillate is withdrawn from the receiving drum 43 through line 46 and, if desired, a portion thereof may be returned to the upper end of the fractionating tower 38 to serve as a reflux therein. Unvaporized residue separated in the separating chamber 35 is withdrawn from the bottom thereof through line 47 from whence it may pass to a storage tank, not shown, or may be subjected to further treatment in a conventional manner.

In accordance with one phase of my invention the total reflux condensate formed in the fractionating tower 38 is withdrawn from the bottom through line 48 as a final distillate fuel oil. According to another phase of my invention a por-

tion or all of this condensate may be subjected to further cracking treatment, as hereinafter described.

When operating in accordance with the latter method the fractionating tower 38 may be provided with a trap-out tray 49 from whence condensate collected therein may be withdrawn through line 50 and forced by means of pump 51 located therein through a separate heating coil 52 located in the furnace 53. The oil, during its passage through the coil 52, is subjected to high temperature cracking conditions after which it emerges through line 54 and may pass through line 55, forming an extension thereof, 15 into the bottom section of the fractionating tower 17 wherein it commingles with the vapors introduced therein through line 16, or, if desired, a portion or all of the cracked products passing through line 54 may be passed through 20 line 56 and introduced into the separating chamber 15 into which the cracked products from the heating coil 12 discharge.

The pressure maintained in the various parts of the equipment above referred to may be substantially uniform throughout, except for the necessary difference to effect the desired flow, or a differential pressure may be maintained between the heating coils 12, 29 and 52 and the separating chambers 15 and 35, in which case the 25 transfer lines 14, 34 and 54 are provided with suitable reducing valves 57, 58 and 60, respectively, to produce the desired reduction in pressure. In practice, it is preferred to maintain the heating coil 12 and separating chamber 15 under 30 a pressure somewhat below that maintained in the heating coils 29, 52 and separating chamber 35. For example, the oil passing through the heating coil 12 may be maintained under an outlet pressure of from 200 to 400 pounds per square 35 inch, whereas the oil passing through the heating coils 29, 33 and 52 may be maintained under a pressure ranging from 400 to 1000 pounds per square inch, for example.

The following example will serve as a guide in carrying out my invention to obtain the greatest benefit therefrom, it being understood that the values given in the example are illustrative rather than limitative.

Mid-Continent reduced crude having an A. P. I. gravity ranging from 20 to 26 is passed 40 through the heating coil 12 regulated to heat the oil to a temperature ranging from 800° to 900° F., preferably between 850° to 875°. The oil is maintained at this temperature for a period 45 sufficient to convert from 15 to 30% thereof into constituents boiling below the boiling range of the original charge, of which from 8 to 15% thereof may be within the gasoline boiling range. The heating coil 12 is maintained at an outlet 50 pressure ranging from 50 to 400 pounds per square inch. The separating chamber 15 is maintained under a somewhat lower pressure, such as from 25 to 100 pounds per square inch. The fractionating tower 17 is regulated to take 55 overhead a fraction having an end point corresponding to that of the desired motor fuel or, if desired, a portion of the heavy naphtha may be condensed within the fractionating tower 17.

Condensate from the fractionating tower 17, 60 upon passing through the heating coil 29 and soaking section 33 thereof, is heated to a tem-

perature ranging from 900° to 1050° F. or thereabouts. The oil is maintained at this temperature in the soaking section 33 for a period adequate to convert from about 20% to 40% thereof into gasoline constituents before merging with the residue from the bottom of the chamber 15. The merged products, during passage through the remainder of the soaking coil 33, are maintained at a temperature of from 850° to 925° F. and preferably between 900° and 925° F. The outlet pressure of the soaking coil 33 preferably ranges from 200 to 600 pounds per square inch.

The top temperature of the fractionating tower 38 associated with the separating chamber 35 is regulated to take overhead the desired distillate products which may have an end point of 15 from 400° to 437° F.

In event condensate from the fractionating tower 38 is subjected to further cracking, this oil, 20 during its passage through the heating coil 52, may be heated to a temperature ranging from 900° to 1050° F. and maintained at a coil outlet pressure of from 200 to 600 pounds per square inch.

Having described the preferred embodiment of 25 my invention, it will be understood that it embraces such other modifications and variations as come within the spirit and scope thereof and that it is not my invention to unnecessarily limit the invention except as necessary to distinguish from 30 prior art.

I claim:

A method of treating hydrocarbon oil to form lower boiling hydrocarbons suitable for motor fuel which comprises passing charging 35 stock comprising the residual constituents of crude petroleum once through a single-pass cracking zone wherein it is subjected to cracking conditions of temperature and pressure to effect conversion into lighter products, directing the resultant cracked products into a primary separating zone wherein separation of vapors from liquid residue occurs, subjecting the separated vapors to fractionation in a primary fractionating zone to separate a reflux condensate from lighter products, passing said reflux condensate through a primary section of a cracking coil under superatmospheric pressure and applying heat thereto to subject the oil flowing therein to cracking temperature and effect conversion into lighter products, withdrawing liquid residue from said primary separating zone and merging said liquid residue with the products from the primary section of said cracking coil for passage 40 through a subsequent section thereof while applying heat thereto to maintain the merged products at cracking temperature and effect conversion into lighter products, passing the resultant cracked products from said cracking coil into a second separating zone wherein separation of vapors from residue occurs, passing the separated vapors into a second fractionating zone wherein the vapors are fractionated to separate a reflux condensate from lighter products, subjecting the later reflux condensate to cracking 45 conditions of temperature and pressure in a separate cracking zone to effect an additional conversion into lighter products and directing the resultant cracked products into the primary 50 separating zone.

RICHARD J. DEARBORN.
